UNITED STATES PATENT OFFICE.

WILLIAM M. KECK, OF COALINGA, CALIFORNIA.

UNDERREAMER.

1,225,968.

Specification of Letters Patent.

Patented May 15, 1917.

Application filed October 28, 1916. Serial No. 128,243.

To all whom it may concern:

Be it known that I, WILLIAM M. KECK, a citizen of the United States, residing at Coalinga, county of Fresno, and State of California, have invented certain new and useful Improvements in Underreamers, of which the following is a specification.

My invention relates to an underreamer, for reaming wells below the bottom of the well-casing, and more particularly to an underreamer adapted for use in combination with a drill-bit.

The object of my invention is to provide an underreamer of such construction that comparatively little wear can occur at any point except the cutting or reaming edge of the cutter member, which may be easily removed and replaced. This is accomplished by providing large bearing surfaces or seats 20 for said cutter, as will be hereinafter fully described with reference to the accompanying drawings, wherein—

Figure 1 is an elevation showing my underreamer, with a drill-bit attached thereto, 25 within the well-casing, the well-casing being shown in section.

Fig. 2 is a vertical section, enlarged, of my underreamer within the well-casing, showing the cutter in retracted position.

Fig. 3 is a transverse section, enlarged, 30 taken in the direction of the arrows on the line 3—3 of Fig. 1.

Fig. 4 is a transverse section, enlarged, 35 taken in the direction of the arrows on the line 4—4 of Fig. 1.

Fig. 5 is a transverse section taken in the direction of the arrows on the line 5—5 of Fig. 2.

Fig. 6 is a transverse section taken in the 40 direction of the arrows on the line 6—6 of Fig. 2.

Fig. 7 is a part-sectional elevation showing the underreamer partly withdrawn into the lower end of the well-casing, the cutter 45 being in its extended, or operative position.

Fig. 8 is a side elevation of the central and lower portion of the underreamer, the cutter being viewed from its face, instead of its side, as in Fig. 7.

Fig. 9 is a transverse section taken in the 50 direction of the arrows on the line 9—9 of Fig. 7.

Fig. 10 is a transverse section taken in the 55 direction of the arrows on the line 10—10 of Fig. 7.

Fig. 11 is a transverse section taken in the

direction of the arrows on the line 11—11 of Fig. 7.

In the drawings, the reference numeral 1 designates the body of my underreamer, 60 which is substantially cylindrical in form, and of a diameter to fit loosely within the well-casing 2. At its upper end, this body 1 is provided with suitable means, as, for example, a tapered screw-thread 3, for attachment to a cable or rod, not shown in the drawings. The lower end of said body 1 is also adapted for attachment to a drill-bit 4, Fig. 1, preferably by means of an internal tapered screw-thread 5. As shown in the 70 drawings, the body 1 of the underreamer is form a slightly eccentric with respect to said end screw-threads 3 and 5 and the axis of the drill-bit 4, for a purpose to be hereinafter set forth.

An axial bore 6 is formed within the body 1, extending upwardly from its lower end, and a radially disposed elongated slot 7 extends from said bore 6 to the exterior of the body. As shown particularly in Figs. 8 and 80 9 of the drawings, the rear or inner portion of said slot is the full width for its entire length, but the outer portion is narrowed at its upper end, as at 8, forming lateral inwardly facing shoulders 9.

A recess 10, Figs. 7, 8, 10 and 11, is formed in the rear wall of the axial bore 6 opposite the wide portion of said slot 7, said recess having a function to be presently described.

Within the slot 7 is carried a cutter member 11 provided with a cutting edge 12. The upper portion of said cutter 11 is formed with a narrow tongue 13, adapted to lie within the narrow slot portion 8, and 95 is provided with shoulders 14 adapted to lie behind and engage the shoulders 9 in said slot, for the purpose of retaining said cutter within said slot. Said cutter 11 is further provided with a rear bearing face, 100 comprising a flat upper portion 15, and a projecting bearing lug 16, Figs. 2 and 7, the latter being semi-circular in form, to seat firmly against the rear wall of the central bore 6.

A substantially cylindrical mandrel 17, slidably mounted within the central bore 6, is provided with a flat forward face 18 against which the flat rear face 15 of the cutter 11 is adapted to bear. A slot 19 is 110 formed within said mandrel 17, within which is received a lug 20 extending rear-

wardly from and preferably formed integral with the upper portion of said cutter, so that both mandrel and cutter move together in a vertical direction.

5 The upper portion or stem 17' of the mandrel is surrounded by a compression spring 21, by means of which said mandrel and the cutter 11 are normally held in their uppermost positions. The lower end of said 10 spring bears upon a key 22 lying within alined transverse slots 23 and 24 formed in the body 1 and the mandrel stem 17' respectively. Said key 22 is notched on its upper side, as shown at 22', the lower end 15 of the spring 21 resting within said notch, and thereby retaining said key in position laterally. When it is desired to remove said key, to permit the withdrawal of the mandrel and the removal of the cutter 11, as 20 will be described more fully hereinafter, the spring 21 may be temporarily lifted out of said notch 22' by means of any suitable tool, not illustrated, inserted through the slot 23 in the body 1, said slot being of 25 sufficient size, as shown in Fig. 8, to permit the entrance of such a tool.

The functional, or working position of the movable parts of the underreamer is shown in Fig. 7. In this position, the cutter 11 is 30 extended, to bring its cutting edge 12 into contact with the side of the well-bore (not illustrated). Ample provisions are made for transmitting the shocks, due to the normal operation of the device, from the cutter 35 11 to the body 1, the upper end of said cutter having a semi-cylindrical seat, at 25, Figs. 7 and 8, in the upper end of the slot 8, and having a bearing for its rear surface 14 against the flat forward surface 18 40 of the mandrel 17. The lower portion of the cutter is supported by the semi-cylindrical bearing of its lug 16 against the wall of the central bore 6.

For retracting the cutter into the body 45 of the reamer, to permit the withdrawal thereof through the well casing, a shoulder 26, Figs. 2 and 7, is formed in the outer face of said cutter, said shoulder engaging the toe of the foot 27 of the well-casing 2, 50 when the reamer is drawn up, as shown in Fig. 7. Continued upward movement of the reamer body causes the cutter 11 and the mandrel 17 to move downward, relatively to said body, until the rear bearing lug 16 55 of said cutter enters the notch 10. This permits the cutter to move into the body of the reamer, and to occupy the position shown in Fig. 2, in which position said cutter is held by the contact of its outer face 28 with 60 the inside of the well-casing. The body 1, being eccentric, bears against the well-casing at its back for its entire length, while said outer cutter face 28 provides a bearing on the opposite side, thus accurately and centrally guiding the drill bit 4, so that the

cutting edges 4' thereof pass freely through the casing. A drainage duct 29, Figs. 2, 7 and 8, is preferably provided for permitting the escape of mud and rock particles from the lower portion of the cutter slot 7. 70

On account of the comparatively large area of the bearing surfaces 25, 15 and 16, of the cutter 11, and the length of the mandrel 17, very little wear occurs at these points, and the body and mandrel therefore last for a relatively long time. The cutting edge 12 of the cutter, however, naturally wears rapidly, necessitating the renewal of said cutter. This may be accomplished very easily, by withdrawing the key 22 in the 80 manner previously described, and allowing the mandrel 17 and the cutter 11 to drop down until the shoulders 14 of said cutter are free of the shoulders 9 in the sides of the slot 7. The cutter may then be withdrawn laterally through said slot. The mandrel, if necessary, can also be easily removed, by allowing it to drop out the lower end of the central bore 6.

Having thus described my invention, what 90 I claim as new and desire to protect by Letters Patent is:—

1. An underreamer comprising a body portion formed with an axial bore and a lineally disposed slot communicating with 95 said bore and having a relatively deep portion, a relatively shallow portion, a semi-cylindrical upper end and a semi-cylindrical back; a cutter member carried within said slot and adapted for lineal sliding movement 100 and swinging transverse movement, said cutter member having a cutting edge adapted to protrude beyond the body when said cutter member lies in the shallow portion of said slot, and to be retracted within said body 105 when in the deep portion of said slot, and said cutter member being further formed with semi-cylindrical bearing faces adapted 110 to seat against the upper end and back of said slot when said member is in the shallow portion thereof, and said cutter member being also formed on its back with a flat bearing face; a lineally movable mandrel fitting 115 closely within the bore of the body portion, said mandrel having a flat face forming a lateral thrust bearing for the flat face on the cutter back; and a connection between the mandrel and cutter member.

2. An underreamer comprising a body portion formed with an axial bore and a lineally disposed slot communicating with 120 said bore and having a relatively deep portion, a relatively shallow portion, a semi-cylindrical upper end and a semi-cylindrical back; a cutter member carried within said slot and adapted for lineal sliding movement and swinging transverse movement, said cutter member having a cutting edge adapted to protrude beyond the body when said cutter member lies in the shallow portion of said 125 130

slot, and to be retracted within said body when in the deep portion of said slot, and said cutter member being further formed with semi-cylindrical bearing faces adapted 5 to seat against the upper end and back of said slot when said member is in the shallow portion thereof, and said cutter member being also formed on its back with a flat bearing face and a lug projecting rearwardly 10 therefrom; and a lineally movable mandrel fitting closely within the bore of the body portion, said mandrel having a flat face forming a lateral thrust bearing for the flat face on the cutter back and having also a 15 slot in which the lug of the cutter member engages.

3. An underreamer comprising a body portion adapted to be passed through the casing of a well, and having means at its upper end for connection with a drilling line and means at its lower end for connection 20

with a drill bit, said body portion being offset laterally with respect to said end connection means; and a cutter member carried within said body portion and adapted to be protruded therefrom and retracted thereinto, said cutter member having an elongated bearing surface adapted to project beyond the side of said body portion when said cutter member is retracted, said bearing surface being adapted to bear against the side of the well-casing and to coact with said offset body portion to guide said drill bit centrally within said casing. 25 30

In testimony whereof I have signed my name to this specification in the presence of two subscribing witnesses. 35
